UNITED STATES PATENT OFFICE.

DOMINIK BÖLDERL, OF OAKLAND, CALIFORNIA.

MINER'S PROSPECTING-TOOL.

No. 874,730.

Specification of Letters Patent.

Patented Dec. 24, 1907.

Application filed February 8, 1907. Serial No. 356,492.

To all whom it may concern:

Be it known that I, DOMINIK BÖLDERL, a citizen of the United States, and resident of Oakland, Alameda county, and State of California, have invented new and useful Improvements in Miners' Prospecting-Tools, of which the following is a specification.

This invention relates to a prospecting implement for miners' use, involving the several features and functions of a pick for excavating, a wedge for splitting rock, a hammer for breaking specimens, and an ax for cutting roots and for like purposes.

The primary object of the invention is to provide for the use of the miner, when on a prospecting tour, a combination-tool that will take the place and fill all the uses of the different separate tools which are ordinarily required on a prospecting trip, and thereby materially reducing the load that the prospector is compelled to carry.

A miners' prospecting-tool of my invention consists of the several parts and features as hereinafter described and claimed.

The accompanying drawing fully illustrates a miners' prospecting-tool of my invention.

Figure 1 is a view of the head and handle of the tool, with the removable pick-points secured to the head when the tool is used as a pick; the head and the attached pick-point on one side are broken away to show the means for securing the head on the handle and the pick-point in the head. Fig. 2 is a similar view of the separable head and handle, with the pick-points removed. Fig. 3 is a top-view of Fig. 2, showing the head broken away in part on one side of the handle-socket. Fig. 4 is a side-view of the ax-blade detached from the head. Fig. 5 is a view of the hammer-head. Fig. 6 is a view of the wedge that is substituted for the pick-point or other detachable member. Fig. 7 illustrates the wedge removed from its handle, so that it may be secured in the head in place of the pick-point or other detachable member.

A miners' prospecting-tool of my invention comprises the cast metal head *a* having a socket *2* for the handle *b*, and on opposite sides of the socket and in the same plane, two bosses *d* *d'*, with square ends *3*. The socket *2* tapers downwards, and the end of the handle is correspondingly shaped, so as to be insertible from the top of the head. Each boss is also formed or provided with a socket *4* extending through it longitudinally from

the end or face *3* into the central socket *2*. From the underside of each boss also, a hole *5* is threaded for a screw *e*, that intersects the socket *4* at right angles.

To the sockets *4*, in the bosses *d* *d'* is fitted the tang *6* with which each detachable member is provided, both the socket and the tang being preferably of circular shape in cross-section, and the base of the tool from which the tang springs being finished square to come solidly to a seat against the boss. The tang of each detachable member is somewhat longer than the hole or socket in the boss, so as to extend into the central socket of the head, and into the handle *b*, when that member is in place, a hole or cavity being formed in the handle to admit the end of the tang as seen in Fig. 1, where the wood of the handle and the metal of the head are cut away to show the tang in place. The tang thus has the double function of attaching the tool to the head and of fastening the handle in the head. Each detachable member is secured in place by its tang being inserted in the socket of the boss and secured by turning up the screw *e*, after the detachable member is brought to a solid bearing against the end of the boss. When the points *f*—*g* are secured to the head *a* as shown in Fig. 1, the tool is converted into a pick; or by removing either or both points *f*—*g*, the hatchet head *h*, or the wedge *k*, or the mallet *m* can be fixed in place.

By fixing the wedge *k* in the supplementary handle *p*, provided for that purpose, the wedge can be employed for splitting by using the mallet upon it; the latter being fixed on the head for that purpose.

Having thus described my invention, I claim:—

1. The herein described prospecting tool, comprising a head having a tapering central socket, a handle removably fitted thereto and provided with cavities, the bosses on the head having squared ends, each boss being provided with a socket extending longitudinally from its end to the central socket, a detachable tool-point or member and a tang secured to the inner end of the tool and adapted to slide into a longitudinal socket, the tang being of a length greater than the socket and arranged to extend therethrough and into a cavity in the handle.

2. In a convertible tool for miners' use, the combination of a head formed with a

tapering central socket and having bosses on opposite sides of the central socket in which are formed apertures, a removable handle therefor provided with cavities arranged to register with the said apertures in the bosses, a detachable tool arranged to be fitted to one of said bosses having a tang secured thereto and arranged to extend through an aperture and into a cavity in the handle to interlock the handle and head,

and a set screw carried by the bosses for securing the tang thereto, substantially as set forth.

In witness that I claim the foregoing invention I have hereunto signed my name in the presence of two witnesses.

DOMINIK BÖLDERL.
